[57] CLAIM

The ornamental design for a video monitor, as shown and described.

DESCRIPTION

FIG. 1 is a front and right side perspective view of a video monitor showing our new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a right side elevational view thereof; and,

FIG. 7 is a left side elevational view thereof.
The swivel mount, control buttons, and the base member are shown in broken lines in the views for illustrative purposes only and form no part of the claimed design.
